UNITED STATES PATENT OFFICE

92,159

DESIGN FOR A BUTTON

Rudolph Louis Bosselman, New York, N. Y.

Application January 20, 1934, Serial No. 50,459

Term of patent 14 years

To all whom it may concern:

Be it known that I, RUDOLPH LOUIS BOSELMAN, a citizen of the United States, residing at New York, in the county of New York, State of New York, have invented a new, original, and ornamental Design for Buttons, of which the following is a specification, reference being had to the accompanying drawing, forming part thereof.

Figure 1 is a face view of the button, showing my new design.

Figure 2 is a side view of the button, showing my new design.

I claim:

The ornamental design for a button, as shown.

R. L. BOSELMAN.
